UNITED STATES PATENT OFFICE.

GREENLEAF WHITTIER PICKARD, OF NEWTON CENTER, MASSACHUSETTS, ASSIGNOR
TO WIRELESS SPECIALTY APPARATUS COMPANY, OF BOSTON, MASSACHUSETTS, A
CORPORATION OF NEW YORK.

PROCESS AND APPARATUS FOR THE MANUFACTURE OF ELECTRICAL CONDENSERS.

Application filed June 8, 1920. Serial No. 387,500.

To all whom it may concern:

Be it known that I, GREENLEAF WHITTIER PICKARD, a citizen of the United States of America, and a resident of Newton Center, 5 county of Middlesex, and State of Massachusetts, have invented certain new and useful Improvements in Processes and Apparatus for the Manufacture of Electrical Condensers, the principles of which are set forth in the following specification and accompanying drawings, which disclose the form of the invention which I now consider to be the best of the various forms in which the principles of the invention may 15 be embodied.

This invention relates to improvements in processes and apparatus for the manufacture of electrical condensers of the sheet type and more particularly of the type 20 wherein mica is used for the dielectric sheets.

The object of the invention is a simplification of the processes heretofore devised by me for making mica condensers consisting of 25 mica sheets and metal foil sheets in permanently intimate contact with one another, the interior of the stack between the sheets being freed as nearly as possible of air, moisture and all materials other than the 30 mica and foil sheets themselves, the mica and foil sheets preferably having nothing whatsoever between them. Dielectric sheets of material having the dielectric and 35 mechanical properties of mica required herein may be employed instead of mica, including its low dielectric losses, its non-porous character and its ability to be formed into thin sheets of sufficient mechanical strength for my processes. The foil sheets preferably consist of lead foil, which is sometimes known in the art as "tin-foil", although other metal foils may be employed.

The invention consists in the processes hereinafter described, and consisting of a 45 small number of steps, wherein the manufacture of the condenser is carried rapidly forward at each of several of the steps; and the process is executed preferably in connection with certain apparatus or equivalents 50 as shown in the accompanying drawings, of which—

Fig. 1 is an elevation, partly in section, of

apparatus employed in dipping in or coating each of the sheets with paraffin and in building the sheets into a condenser stack 55 as shown in Fig. 2, or into sections which may be used in a sectional condenser shown in Fig. 2^A.

Fig. 2 is an elevation of such a condenser. Fig. 2^A is an elevation of such a sectional 60 condenser.

Fig. 3 is an elevation showing a sectional condenser like that of Fig. 2 (but which may be a condenser like Fig. 2^A), showing also a permanent small spring clamp applied to the stack and adapted to be permanently embedded with the condenser and inserted with it in the permanent condenser 65 casing of Fig. 4. Fig. 3^A is a plan view of the same which better shows the clamp. 70

Fig. 4 is an elevation (partly in section) showing the condenser, with its clamp, inserted into its permanent casing 29, and thus far not provided with a cover for the 75 casing.

Fig. 5 is an elevation, partly in vertical section, showing the apparatus of Fig. 4, but with a temporary paraffin head 30 secured to the top of the casing 29, the latter being heated. Fig. 5^A being a similar view 80 of a modification of the process of Fig. 5.

Fig. 6 is an elevation of the apparatus of Fig. 5, with the addition of a powerful 85 press 27 to initiate the desired high mechanical compression on the condenser, which pressure thereafter is to be maintained by the permanent small clamp.

Fig. 7 is a diagrammatic view of apparatus employed for the purpose of cooling the mass of paraffin surrounding the 90 condenser in connection with the filling process of Fig. 5; Fig. 5^A illustrating a modification of this cooling process.

Fig. 8 is an elevation (partly in section) 95 showing condenser in its completed form, with cover applied to the casing; Fig. 8^A being a similar view of a similar condenser, but modified in conformity with the modified filling and process of Fig. 5^A.

Fig. 9 is a modification of the operation 100 of Figs. 5, 6, 7 and 5^A.

The simplified process for a simple unitary condenser as in Fig. 2 preferably includes but seven steps which correspond gen-

erally with the numbering of the drawings 1 to 7 inclusive. The same steps apply to a sectional condenser as in Fig. 2^A, but with certain treatment interpolated. These steps, 5 briefly, are as follows:

First, dipping each mica and foil sheet in warm molten paraffin in the apparatus of Fig. 1.

Second, building a stack of such dipped 10 or coated sheets as shown in Fig. 2 or 2^A, this building being done, if desired, in the apparatus of Fig. 1. (At this stage, if the condenser is to be sectional, there will be 15 interpolated certain treatment to be described.)

Third, applying to the built-up condenser stack a small permanent spring clamp as shown in Figs. 3 and 3^A.

Fourth, placing the condenser with its 20 clamp of Fig. 3 in the permanent condenser casing of Fig. 4.

Fifth, filling around the condenser, with 25 clamp in place, and in its casing of Fig. 4, with hot molten heating embedding paraffin as shown in Figs. 5 and 5^A, either with the use of a high paraffin-head as in Fig. 5 or by inverting the apparatus of Fig. 4 as 30 shown in the modification of Fig. 5^A; and either with the application of the heating means of Fig. 5 or two or more fillings of 35 highly heated paraffin or both.

Sixth, supplying permanently-maintained 35 pressure on the condenser while hot, as by the means shown in Fig. 6.

Seventh, cooling and solidifying the embedding paraffin around the condenser in 40 its final casing, as shown in Fig. 7; whereupon are conducted the final steps of completing the condenser in the form shown in Fig. 8 or 8^A.

The condensers made by the processes hereof are more particularly adapted for 45 use under conditions where it is important that there shall be minimum electrical losses in the condenser in service, as in radio telegraph transmitters or in power lines, laboratory standards and the like. The condenser stack, in any case, may be employed as a unit as in Fig. 2 in any desired way, or it

50 may be constructed in sections as in Fig. 2^A which may be grouped in service in any desired relation of series, parallel or series-parallel, or the condenser may be constructed into sections permanently connected 55 in series, as in the radio telegraph transmitting use where the condenser is not only constructed with sections insulated from one another in the well-known way, but the sections are permanently connected in series 60 in the well-known manner.

As the first process, all the sheets, of both mica and foil, are coated with the paraffin which serves later as a detergent for washing out air and moisture from between the 65 assembled sheets,—later steps being em-

ployed for the purpose of squeezing out this paraffin from between the sheets to the greatest possible extent with the view of leaving a condenser stack consisting only of the sheets of mica and foil, preferably freed from all the paraffin which has been temporarily employed for the purpose of washing out the other undesired foreign materials, i. e., air and moisture. This coating may be done by treating the loosely-assembled sheets in a bath of hot paraffin; but the greatly preferred process is that as in Fig. 1 of separately coating each sheet with the paraffin, this being done preferably while the process of building up the material-stack out of the separate sheets is being effected, this preference being due to the fact that the sheets when wet with paraffin or held together by the hardened paraffin are much more conveniently held together at this stage of the processes than when dry.

Fig. 1, in elevation, shows the building stand consisting of a horizontal metal plate 1, two vertical posts 2 at the rear, each of 90 these posts being cut away at 3 to aline and guide the sheets of mica during the operation of building the material-stack; and four legs 4 are provided on the bottom 1.

In Fig. 1, the above building stand is 95 shown as placed in a waxing tray 5, the latter being heated by a very small Bunsen burner 6 to keep simply warm the paraffin shown in said tray. In this molten paraffin, the operator dips each mica and foil sheet, 100 and the temperature of the paraffin in tray 5 during the dipping and building operation is about 70° centigrade, i. e., about the temperature which the operator's fingers 105 conveniently can endure. After each sheet is dipped, it may be allowed to cool and stored for future use in the second or building operation. Preferably, however, the sheets are built into a stack when freshly 110 dipped and hot, which is the reason why the building stand in Fig. 1 is shown standing inside of waxing tray 5.

Second or building operation.

The condenser may be built completely 115 under a bath of paraffin, but preferably it is built as in Fig. 1 in atmosphere with its lower end in heat-conducting relation through base 1 of the building stand with the paraffin in tray 5. This building in 120 atmosphere permits less exposure of the operator's fingers to the heated paraffin. The legs 4 of the building stand hold base 1 thereof away from the base of tray 5, so that the heated paraffin can circulate freely 125 around base 1. The base 1 is heated during the building operation by the warm wax, and hence during the building operation the condenser being built is kept warm, i. e., both by the warm coatings on the sheets 130

and by the heat conducted from the warm paraffin in tray 5 to the metal base 1 and metal posts 2, and by the heat conducted upwardly by the growing stack itself. This maintenance of heating during the building operation assists in keeping down unnecessary thickness of the coating paraffin between sheets (due to the increasing tendency of the growing stack to squeeze out excess paraffin by gravity) and also assists in tending to avoid the entrapping of air in the stack at this stage (due to the tendency to greater intimacy of the sheets and the consequent tendency of the liquid paraffin which is being squeezed out to wash out air and moisture from between the sheets rather than to permit entrance or entrapping of air between the sheets). If the condenser during the building operation be comes insufficiently warm, or if it appears to the operator to have become solidified, she may spoon up paraffin out of tray 5 and pour it over the condenser from time to time for the purpose of keeping warm and soft the paraffin between the sheets.

As the operator puts each foil sheet in place on top of a mica sheet, she can and should observe whether any air bubbles are entrained in the paraffin (as due possibly to incomplete dipping in the paraffin in tray 5), and if there be, and preferably in every case, she smooths down (squeegees) each foil on the stack to squeeze out such air.

Likewise, in putting each dipped mica sheet in place on top of a foil sheet, she presses the mica sheet down on the coated foil sheet beneath it, for the same purpose of squeezing out any air. But in any case the squeegee pressure applied should be slight, to avoid so compressing the stack that when the pressure is released air would enter, due to the springing apart of the resilient mica sheets after too great compression.

Preferably, the mica sheets have been selected to be of uniform thickness, so that, by the operator's counting of such sheets during the building operation, the capacity of the stack may be known at any stage of the building operation, and so that a condenser of a given desired capacity may be built up out of a definite number of sheets. Thus a given condenser stack as 10 of Fig. 2 may be built up in the apparatus of Fig. 1; or, as shown in Fig. 2^A, the condenser may be built up therein in the form of a sectional condenser, the temporary markers 11 of Fig. 1 being placed on top of each section as it is built up to the desired capacity. Thus the building operation of Fig. 1 may result in a unitary condenser as in Fig. 2, or in a succession of sections with intervening markers and adapted to be completed as a sectional condenser as shown in Fig. 2^A wherein the

temporary markers 11 of Fig. 1 are replaced by permanent insulating separators 11^A which are placed to project alternately at opposite sides of the stack as shown in Fig. 2^A and as has been customary for 70 many years.

After the condenser has been built to the desired capacity, or succession of capacities, the building stand may be removed from the tray 5 and the condenser allowed to cool in the building stand sufficiently to permit convenient handling for the third step of applying the permanent clamp, without impairing the unitary character of the stack consisting of the sheets temporarily held in alinement by the paraffin coatings. At this stage, the paraffin in and about the stack comprises not only the paraffin between the sheets in the interior of the stack but also the so-called marginal paraffin which is that between those portions of the foils which project out beyond the mica stack. When the stack is thoroughly cooled and the paraffin hardened, the projecting foils 12, at the respective 80 ends of the stack as shown in Fig. 2, are soldered together so that the foil bunch at each end constitutes a unitary conductor, and to such respective foil bunches are soldered the strip leads 13 and 14 which 90 constitute the terminals of the condenser. In the sectional condenser of Fig. 2^A, at a like stage of operations, the same thing may be done in respect of each section, whereupon the foil bunches of the respective sections are soldered to the foil bunches of adjacent sections in the usual manner as shown in Fig. 2^A; the condenser terminals 13 and 14 being thereupon soldered to the two end sections respectively. In the case of either 100 Fig. 2 or Fig. 2^A, the upper condenser lead 13 now has soldered to it the upper condenser terminal 15; and the lower condenser terminal 14 has soldered to it the lower condenser terminal 16, all in preparation for 105 the third or clamp-applying operation.

In the case of a sectional condenser, certain treatment is interpolated (as referred to generally above) at the stage before the third or clamp-applying operation and before the assembly into sections of Fig. 2^A, and after the completion of the building of a sectional condenser material-stack indicated in Fig. 1 wherein the sections are separated by the temporary separating 115 markers 11. This interpolated treatment is as follows. The just-built stack of such sections of Fig. 1 is thoroughly and highly heated by immersion in a bath of hot paraffin (at about 150° C.) so as to permit the 120 application of such pressure as will simulate final compression on the eventual condenser stack in order to permit of measurement of capacity. Each section might be heated separately (it is to be tested separately), 125

but it is more convenient to heat all the sections together in the form of the stack. Then the highest practicable mechanical compression is applied; and this may be 5 while the stack is in the heating bath, after being thoroughly heated therein, or just after being removed from the bath and while yet thoroughly heated. Thereupon the stack of sections (or the individual sections) are 10 allowed to cool while said mechanical compression is maintained. Thereupon each section is tested for capacity, and, if not correct, the capacity is adjusted. Preferably this is effected by previously and initially 15 building each section with more sheets of mica and foil than the number calculated for a "run" of the thickest mica, so that upon this test, the capacity will either be just right or a little too high, so that the 20 capacity may be corrected by removing one or more of the sheets. Then each section is tested for voltage breakdown, and sections shown by this test to contain bad mica sheets are treated by splitting the sections 25 in half, testing the halves, and putting together good halves of different sections; and in splitting the bad halves, bad quarters, bad eighths and bad sixteenths, and similarly combining the good portions into complete good sections. Thereupon the good 30 and correct sections are assembled as in Fig. 2^A. The condenser of Fig. 2^A thereupon is put in a press such as the arbor press 27 of Fig. 6, the press is operated, and the 35 capacity of the entire condenser measured under compression. Then the compression is relaxed and any necessary adjustment of capacity of the stack is made, this, however, being rarely necessary. If the test shows a 40 broken-down section, such section is replaced with a tested good and accurate section, and if the test shows faults in soldering together the foils of adjacent sections, then the soldering is perfected. Thereupon such sectional 45 condenser is in readiness for the third or clamp-applying operation, which at this stage may be employed also on the single unit condenser of Fig. 2, upon which the above interpolated steps are not necessary. 50

Third or clamp-applying operation.

At this stage, no substantial compression is put on the condenser, the clamp being simply assembled with the condenser in preparation for further operations. 55

The clamping means shown in Fig. 3 is sufficiently massive and strong to maintain permanently the compression later applied to the condenser, but it is small enough to be assembled permanently with the condenser and be received therewith in the permanent casing for the condenser. This clamp is preferably a spring clamp adapted to permanently apply a live pressure to the stack during the later stages of the proc-

ess and permanently in service, during which times the temperature of the stack varies and consequently its length also. The spring clamp yields to conform to such varying length and without injury to or deformation of the condenser it maintains the desired uniform live pressure. 70

As shown in Fig. 3, the condenser (illustrated, for example, as a sectional condenser as in Fig. 2^A, although it may be the simple condenser of Fig. 2) is placed on a base 17 which may be of metal. In fact this base plate 17 may rest on the base 1 of the building stand of Fig. 1 before the building of the stack (as shown therein) so that the condenser on such plate 17 may be removed with said plate from the building stand, in such case plate 17 being provided with holes (not shown) corresponding to posts 2 of Fig. 1, so that it may be slipped down over and up off from said posts. This plate 17 forms the base member of the clamp, and it may be a resilient steel plate. On the top of the stack in Fig. 3 is placed an insulating sheet 18, which may be of mica or bakelite, and on top of this is placed a steel plate 19, which serves to transmit to the condenser the compression applied from the two clamping members 23 to be described. On top of the steel plate 19 is placed a steel spring plate 20 which may be the principal resilient member of the clamping means and which when not compressed assumes a bowed or convex form (not illustrated). Above this top spring plate 20, the upper or high potential condenser lead 13 is bent down, having soldered to its end the condenser terminal 15. On top of plate 20 are placed two insulators 21, each of which may consist of a stack of mica sheets, these serving to insulate the metal clamping members from the upper or high potential end of the condenser. On top of mica stacks 21 respectively are placed two metal clamping members 23 (Fig. 3^A). Adjusting screws 24 secure clamping members 23 to side bars 22 which at their bottom are secured to base plate 17 by screws 25 and 26 respectively. Later on, these screws 25 and 26 hold the resilient plate 20 in flexed condition to apply the pressure resiliently to the condenser, the adjustment being permitted by top bolts 24. In some cases (to be described) screws 25, 26 at the bottom may be the adjusting screws, in which case base plate 17 may be the resilient member of the clamp. The insulators 21 should have sufficient thickness to prevent discharge between the top of the condenser and the upper metallic portions of the clamping means. Also said metal parts of the clamp preferably are copper-plated in order to prevent losses in service by eddy currents in such parts. 115

The condenser with the clamping means now applied but not yet acting to any sub- 120 125 130

stantial extent, save to permit handling the condenser as a unit, is now ready to be inserted in the permanent casing.

The design of the clamp is such as to permit it to be received in the casing, and to the end of obtaining an efficient clamp in such small space, the screws are provided as described. While these screws and the entire clamp are designed to be ample to maintain permanently the high degree of compression to which the condenser is subjected later in the press of Fig. 6, yet these screws are not adapted to permit such compression to be initially applied by turning them, and hence the use in a later step, of the press of Fig. 6. At this stage, no very great compression is put on the condenser, the clamp being simply more or less loosely applied to the condenser.

Fourth operation, placing in casing.

This operation consists simply in placing the condenser with clamp loosely applied into its permanent casing 29 as shown in Fig. 4. (Here the final cover 38 is shown in dotted lines indicating that it is not yet applied.) The metal casing 29 is preferably a casting and formed with internal grooves 43 to receive the metal clamping members 23 to center the condenser in the casing, the bottom plate 17 of the condenser being received and held in a space in the bottom of the casing located between ledges 44, all whereby the condenser is in heat-conducting contact with the metal casing by way of the metal clamping member or plate 17. The permanently-clamped condenser, now permanently located in its casing, is now ready for the

Fifth or wax filling and heating operation.

By this operation, the condenser casing is filled around the condenser with its final embedding paraffin and thoroughly and highly heated in preparation for its sixth or compressing and cleansing operation, whereby the paraffin coatings heretofore existing on the sheets are squeezed out permanently, thereby washing out air and moisture from between the sheets.

One manner of executing the filling and heating operation is shown in Fig. 5, wherein, before the filling, the temporary waxing head 30 is applied to permanent casing 29 and the hot paraffin is supplied through the hole 80 to fill the entire casing and head, and wherein the gas burner 81 is used to secure adequate heating. If desired, however, as an alternative or auxiliary manner of heating, the casing 29 can be filled with a temporary hot paraffin bath, which is then decanted, in order to preliminarily heat the condenser prior to the application of the temporary head 30 and the filling of the final embedding paraffin. Such possible temporary heating bath may or may not be

used in addition to the use of the burner 81,—the principal operation being the same in any case, i. e., to co-operate in adequately heating the condenser in connection with the final paraffin embedment and the subsequent special compression. Among other permissive variations of the heating operation is that of a continuing flow of hot paraffin through the condenser casing, which may be effected by providing a small hole in the bottom of the casing and a continuous supply of hot paraffin to the top.

The purpose of the temporary head 30 and its filling at this time is to facilitate the proper conduct of the operation of solidifying the embedding paraffin after the step of compressing the condenser.

The head 30 is provided with a central tapered internal pin or projection 33 depending from the top and having a hole drilled in its lower end to receive the threaded upper condenser terminal 15 which is soldered to flexible lead 13. This construction not only co-operates (in centering the condenser) with the small clamp and the casing grooves (Fig. 4), but holds up terminal 15 and lead 13 so that embedding paraffin may fill the space between lead 13 and the top of the condenser. For the purpose of keeping the paraffin (with which the apparatus is to be filled) away from the upper part of the condenser terminal 15, a nut 34 is threaded on terminal 15, and a rubber washer 35 is placed between nut 34 and the lower end of tapered projection 33. Of course, nut 34 and washer 35 are put in place on terminal 15 before temporary head 30 is applied to casing 29, the nut 34 being first screwed down into or slightly above its proper position and thereafter the head and its tapered internal projection 33 are placed on top of the casing and on top of the washer 35 respectively. The tapered projection 33, together with the external tapering of the entire head 30, provide an internal space which is tapered annularly, in order the more readily to permit the removal of the head later on from the paraffin which by that time has hardened in said annular space in the head.

The object of the thorough and high heating of the condenser at and about the time of the filling operation and the subsequent compressing operation is to cause the removal (especially by way of the compressing operation), of air and moisture vapor from between the sheets of the condenser and from the margins and vicinity of the condenser.

In Fig. 9 is shown a modification of the operation in Fig. 5, wherein the condenser and the apparatus associated with it is set at an angle so that any air or vapor entrapped between the projecting ends of the foil sheets and projecting separators may be permitted to move upwardly through the bath of wax

and away from the vicinity of the condenser, this being permitted by the highest practicable heating of the condenser and the paraffin. This inclined position of Fig. 9 may be maintained not only during the fifth or wax filling and heating operation of Fig. 5, but also during the compressing operation of Fig. 6, and, if desired, during the solidifying operation of Fig. 7. Likewise, this inclined position of Fig. 9 may be maintained in connection with the modified operation of Fig. 5^a.

In preparation for the compressing operation of Fig. 6, the condenser should be so thoroughly heated that all the paraffin on the surfaces of the sheets inside the stack may become liquefied. Depending upon the various permissible ways of applying heat, this heating may require from half an hour to several hours, the temperature of the paraffin bath being maintained at substantially 135° C., or, in other words, as near as practicable to the melting point of the foil sheets. This fifth operation of wax filling and heating in final embedding paraffin is preliminary to the sixth or compressing and cleansing operation.

In this invention, the operation of squeezing the wax coatings from out of the stack and the consequent washing out of air and moisture is conducted after the condenser is inserted in its final casing and after such casing is filled with the final embedding paraffin. Thus at no time subsequent to the sixth or compressing operation is the condenser exposed to the atmosphere, and therefore no vacuum treatment is necessary prior to or during the filling in of the embedding paraffin, provided that the filling and heating and the compressing operations are effected under the conditions specified herein or by equivalent operations so that not only are the air and moisture removed from the interior of the condenser, but also from the vicinity of its exterior. Likewise, the invention hereof makes unnecessary the employment of any squeezing out or compressing operation prior to the filling in of the final embedding paraffin. Likewise, if heating means are employed as in Fig. 5, no heating bath prior to the filling in of the embedding paraffin need be employed.

Upon the proper conduct of the above-described filling and heating operation, the condenser is ready for the

Sixth. or compressing and cleansing operation.

The condenser with the apparatus of Fig. 5, and as yet not highly compressed in its resilient clamp, is then placed in a press such as the arbor press 27 of Fig. 6. Preferably, the arrangement is such that the condenser may be in the inclined position

shown in Fig. 9. In either case when the press of Fig. 6 is used, a head without the part 33 should be used. During the operation in Fig. 6, the condenser yet should be highly heated and maintained hot, so that the paraffin coatings on the sheets in the condenser may be liquid. For this purpose, it may be desirable to maintain heating by the manual application of the flame of a gas burner 82 or in any other suitable manner, so that the conditions are ready for washing out the interior of the stack by the squeezing of the compression.

As a rule, it is better to resort to the press 27 of Fig. 6, rather than to attempt compression by way of the small permanent clamp as by the use of the socket wrench 32 of Fig. 5, for in the press of Fig. 6 the condenser readily may be subjected to the highest practical mechanical compression, which is desired. The vertical reciprocating standard 35 of the press has an opening 36 at its lower end adapted to permit the reception of the upper or high potential terminal 15 of the condenser; and the lower end of standard 35 is applied to the top plate 20 of the condenser at a point between the clamping members of the permanent small clamp. This press 27 is employed when, as is usually the case, the small permanent spring clamps are designed (as shown in Figs. 3 and 4) for the purpose of permitting the clamps to occupy a small casing with the result that the clamp is not adapted to initiate the highest practicable compression desired; but, if other designs of clamp be employed by virtue of which they are adapted to initiate such high compression (it may be permitted by the use of a larger casing 29), then the large press 27 need not be employed.

In the compressing operation, the pressure to which the condenser is subjected is approximately one thousand pounds per square inch of the active area of the mica sheets, i. e., the area of the overlapping portions of the foil sheets in the interior of the condenser.

While the compression is yet maintained by the press 27, the permanent small clamps are screwed up to maintain such compression as by means of a suitable socket wrench 32 (Fig. 6) with handle 33, acting on the bolts 24, so that the permanent clamps thereafter hold the condenser under the pressure initiated by the large press 27.

By the application of this pressure, the thin paraffin layers between the sheets, in liquid condition, are substantially squeezed out from the interior of the condenser, carrying with them substantially all of any entrapped air or moisture and thereby improving the serviceability of the condenser by removing such causes of electrical losses or breakdowns in service.

The application of heat, as by the flame of gas burner 81 of Fig. 5 is advantageously continued not only before and during the compression, but also after the compression, and preferably during the maintenance of the condenser in the inclined position shown in Fig. 9. This continuation of heating may be effected while the condenser and its associated apparatus are left in position in the large press 27 of Fig. 6, or the condenser and its associated apparatus may be restored to the location of Fig. 5 above burner 81, or preferably in the inclined position of Fig. 9. This continuation of heating is for the purpose of permitting the rise up through the hot embedding paraffin of any air or vapor existing about the margins of the condenser as the result of the compressing and squeezing out operation; and the time of this continuation of heating is included in the several hours of heating above specified.

The heating is to be continued, in any case, until the cessation of emergence of all air or vapor bubbles from the surface of the molten paraffin in the top of head 30, including such air or vapor as may have been caused to emerge from between the sheets by the compression of the hot stack. The time of continuance of the heating after the compressing operation is governed adequately in any case by such observed action of the emergence of bubbles from the top of the molten paraffin. It is preferable that all the necessary heating of the condenser be effected in the bath of embedding paraffin as by the continued application of heat thereto, instead of by the employment of a pre-heating bath. If desired, however, the continuous flow of heating paraffin above described in connection with Fig. 5 may be effected after the compressing operation and especially in connection with the inclined arrangement of the condenser, as shown in Fig. 9, instead of the vertical disposition shown in Fig. 5, as an alternative to the use of burner 81. In such case, as above stated in connection with Fig. 5, a hole 83 (Fig. 9) may be provided in the bottom of the casing for the exit of the paraffin continuously supplied to the top of head 30. This hole may be closed permanently by a screw plug to stop the circulation. The continuous flow of hot paraffin down between the inclined surfaces of the projecting ends of the foil sheets serves to wash away air or vapor entrapped in the margins of the condenser. When this purpose has been accomplished, the hole 83 may be closed, the condenser being then ready for the final or solidifying operation of the paraffin remaining in the casing, which is now the final embedding paraffin;

for, inasmuch as the condenser has been surrounded by molten paraffin continuously since the compressing operation, and therefore not exposed to the atmosphere, no further treatment prior to the solidifying operation is needed, for no air or moisture can get into the highly compressed stack or adjacent to the condenser while surrounded by the hot paraffin which, of course, by its heating, has been freed from air or moisture.

When the heating has been continued to the desired extent of driving the air and vapor out of the paraffin in casing 29 (it is not important that they be driven out from the paraffin in head 30), the conditions are such that the apparatus is in readiness for the

Seventh or solidifying operation.

This process is that of cooling the paraffin which has been poured into casing 29 around the condenser as in Figs. 5, 6 or 9.

This operation is illustrated in Fig. 7.

The function of temporary head 30 is to assist in causing proper cooling and prevent the formation of voids in the embedding paraffin of the casing around the condenser, thereby producing a holosteric embedding. During the process of cooling, the paraffin in the casing and head decreases largely in volume, and this contraction, in the absence of the high head 30, would result in the formation of cracks and voids in the paraffin in the upper part of the casing in the vicinity of the high potential upper end of the condenser. These voids or cracks are liable to be filled with gases or vapors entrained in the paraffin or with atmosphere drawn in from outside the paraffin. Such cracks or voids in the vicinity of the high potential end of the condenser would be liable in service to result in losses and undue heating. By means of the paraffin in the high head 30, however, there is maintained a substantial head of paraffin which bears down on the surfaces of solidification during cooling, thereby closely following up the shrinkage and at all times and places preventing formation of voids in the paraffin in the casing around the condenser, especially in the vicinity of its upper or high potential end. During the cooling, additional hot paraffin is poured into head 30 to compensate for shrinkage during cooling and solidification and to keep the head full, and this addition of hot paraffin keeps liquefied the paraffin in the upper part of the head. Of course, voids or cracks in the paraffin in the upper part of the head will be formed finally upon solidification of such paraffin, but one object of the temporary head is to provide a sufficient volume of paraffin above the permanent embedding

paraffin in the casing so that all cracks or voids which are formed will be formed in the paraffin in the head and not in the permanent paraffin embedding in the casing.

5 As an example of the general size and proportions of the temporary head 30, it may be stated that for a condenser casing 29 about $3\frac{1}{2}$ inches high and $4\frac{1}{2}$ inches long by 3 inches wide (internal dimensions), the temporary head 30 may be of the same length and width and of at least the same height; but, as shown in Fig. 5, the head may be of greater height, and may be advantageously even higher and larger than shown. While a much shorter head than here specified will tend to prevent some of the voids in question, yet it is extremely important to employ a head of substantially the height here specified, in order to prevent voids in the paraffin around the upper or high potential end of the condenser.

Preferably, the above cooling process is so conducted as to cause the solidification to proceed from the bottom of the casing 25 upwardly to the top of the temporary head, i. e., causing the cooling to proceed more slowly at upper parts of the paraffin in casing and head, for in this way the functions of the temporary high head are best 30 executed. This cooling from the bottom upwardly may be effected either (1) by abstracting heat from the bottom of the embedding paraffin and without doing anything to the top paraffin, or (2) by applying heat to the top paraffin while permitting the bottom to gradually cool upwardly as by room temperature, or (3) by abstracting heat from the bottom while simultaneously applying heat to the top. Specifically, 35 the latter is preferable for economy of time and in giving better control of the progressive cooling. In practice, the last or preferable manner is effected (Fig. 7) by cooling the bottom by an air blast from fan 67 while heating the top paraffin by means of heated copper strips 68 which extend down into the top of the paraffin in head 30. The casing 29 rests on supports 69 which raise it above a table or bench; and the blast from fan 67 is directed by a sheet metal frame 70 toward the lower part of a side of the casing 29 and the bottom between the supports 69; the upper part of frame 70 serving as a shield to prevent the air blast from contact with the upper part of casing 29 and the head 30. The copper strips 68 have their outer ends brought near together and both are heated in the flame of a Bunsen burner 71; the heat being thence conducted to the other and bent-down ends of the strips which extend down in the paraffin, those ends being separated from the head 30 by heat-insulating members 72 of felt or the like. Ad-

ditional heat is imparted to the paraffin in head 30 by the hot paraffin which is added thereto from time to time to compensate for the shrinkage of the lower and cooling portions of the paraffin.

After solidification is completed, by any 70 equivalent process of filling and cooling, head 30 is removed from casing 29 and from the paraffin body above the casing, this removal being readily permitted (on account of the tapered internal annular surfaces of 75 the head), upon the application of a gas flame to the outside of the walls of the head. Then, by means of a long knife, the paraffin body above the casing is cut and chipped off and then pared and shaped to a level with 80 the top of the casing. The device is now completed save for the application of a suitable cover 38 (Fig. 8) of insulating material such as fiber, bakelite or the like. This cover has a central opening for the 85 threaded condenser terminal 15 and a lower recess for the nut 34 and rubber washer 35. When the cover is put in place and secured to casing 29 by screws 53 (Fig. 8), nuts 54 are then threaded on the terminal 15 and 90 are pinned together and another nut 55 are screwed on top of them. Terminal 15 is one 95 terminal of the condenser and may be the high potential terminal; and the other or low potential terminal may be the casing 29 when that is of metal, the bottom section of the condenser being electrically connected to the casing as shown in Fig. 8 at 14 and 16.

In Fig. 5^A is shown a modified method of 100 executing the processes of filling and compressing the condenser illustrated in Fig. 5. This method consists in inverting casing 29 during the filling, compressing and cooling 105 operations; and this involves a modification 110 consisting in having a casing with its bottom open as well as its top, and a separate bottom member finally secured to the bottom of the casing as shown in Fig. 8^A as a modification of the assembly shown in Fig. 8. 115

As shown in Fig. 5^A, the cover 38 is applied to the casing before the condenser (with its permanent small clamp loosely applied) is inserted in the casing 29; and then the casing, with temporarily open bottom 115 as shown in Fig. 5^A, is inverted to receive the filling of hot molten embedding paraffin. By this method, the high potential end of the condenser is located at what is temporarily 120 the bottom of the casing (i. e., until the solidification of the embedding paraffin), so that the fluid paraffin in the casing constitutes a fluid head above the high potential end of the condenser, and so that when the process is executed of solidifying the embedding paraffin from the bottom upwardly, 125 the paraffin will solidify first around the high potential end of the condenser, and the

fluid paraffin thereabove bears down upon the upwardly moving surface of solidification, thereby preventing the formation of voids or cracks in the paraffin near the high potential end; and any cracks or voids in the paraffin near the low potential end of the condenser (i. e., in what is to be the bottom of the casing) will be relatively innocuous. Also the paraffin by this method is caused to adhere to the inside surface of the cover 38 of the casing, as the result of the paraffin being applied thereto when hot and molten, thereby filling up with permanent embedding paraffin any air spaces near the high potential end of the condenser which might permit brush discharging in the service of the condenser.

By this operation, the use of the temporary waxing head 30 of Fig. 5 may be omitted; although in any case it may be employed wherever it is desirable to insure against the formation of all cracks or voids anywhere within casing 29, even at what is finally to be the bottom of the casing; for the presence of voids, even in the vicinity of the low potential end of the condenser, might be deleterious, in that they might rise up toward the high potential end if the condenser were subjected to such service as to heat it to such extent as to liquefy the embedding paraffin.

In executing the above-described method with Fig. 5^A, the same general processes of filling, of compressing and solidifying, may be employed, as above described; and in particular, the heating of the paraffin will be followed out to the proper extent for liquefying the paraffin on the surfaces of the sheets in the condenser preliminary to the application of the squeezing-out compression; and in the continuance of the heating to such extent as to permit the upward passage of air or gas bubbles from out of the casing 29 to the upper part thereof (or up into the temporary head, in case that be employed).

In Fig. 5^A, on account of the inversion of the condenser, the screws 25 and 26 at the bottom of the condenser (Fig. 3) will be the adjusting screws at the top in Fig. 5^A, in order that they may be accessible for adjustment on the upper end in the inverted position of the condenser, so that the compression may be applied through the open end of the condenser. In this case, base-plate 17 may be the resilient member of the clamping means. This inverted modification is better adapted to instances wherein the compression is initiated by way of the small clamps and without the press 27 of Fig. 6, in instances where the cover 38 is of insulating material. But where cover 38 is of metal, the press 27 may be employed.

After the previously-described cooling and solidifying process has been executed

on the apparatus of Fig. 5^A, a permanent base plate 39 (Fig. 8^A) is applied to the bottom of the condenser by suitable screws, to close up the casing, a gasket 42 being placed between the main casing and base plate 39.

In any case, the solidifying operation may be conducted with the condenser in the inclined position shown in Fig. 9; but this is not necessary or desirable in instances where air and moisture have been eliminated by the compressing and heating operations described above.

If desired, one or a number of condensers (each in its permanent casing and finally clamped) as in Fig. 5 but without any head 30, may be placed in the bottom of a very large tank filled with molten embedding paraffin to a considerable height so that a large head of molten paraffin is located above the condensers; and then the mass of wax solidified and the various condensers separated from the mass and all the wax removed from each save that inside the casing around the stack. For convenience, such large tank may have its sides detachable to facilitate the removal of the condensers from the mass of hardened wax. This modification obviates the placing of a waxing head 30 on each casing.

Whenever compression or clamps are referred to herein, such compression is to be understood to be preferably the highest mechanical compression which is practicable to be applied on the soft lead-foil sheets, and this in practice is about 1,000 pounds or more per square inch of the active area of each mica sheet, i. e., that part of the mica sheet which lies between the overlapping foil sheets, this being a pressure which amounts to about a ton or more on the entire end surface of an ordinary condenser 3" high by 2" long by 1½" wide.

When the word paraffin is used in the claims, it is intended as applying to any material which is the substantial equivalent of the embedding material preferred herein, which is a mixture of paraffin and canauba wax.

As to the limitation to sheets of mica, it is to be understood that this does not exclude other materials which might be found to be equivalent within the invention, as to the valuable properties of mica for this purpose involving its low dielectric losses, high dielectric strength and its ability to be formed into thin sheets of sufficient mechanical strength for my processes.

I claim:—

1. The herein-described method of making a condenser which consists in submerging a stack in a bath of fluid insulating material in a casing and then, while in said bath, applying permanent pressure to the stack to drive out insulating material from between

the sheets and bring the sheets thereof into intimate relations, forming in said casing a permanent filler of such insulating material around the stack without exposing the stack to atmosphere after its submerging.

2. The herein-described method of making a condenser which consists in first subjecting a stack to a bath of fluid insulating material and to heat in a casing to drive out moisture and air and then, while in said bath and heated, subjecting the stack to high permanent pressure to bring the sheets of the stack closer together and drive the insulating material and any contained air or moisture from between the same, forming a permanent filler around the stack of said insulating material in which it is submerged without exposing the stack to atmosphere after its bath therein.
3. The herein-described method of making a condenser which consists in building a stack of sheets with liquefiable insulating material between the sheets, placing said stack in a casing in position to be permanently clamped, subjecting the stack in said casing to a bath of molten insulating material and to heat to liquefy the insulating material between the sheets and drive out air and moisture, applying permanent pressure to the stack while in the bath and while heated to bring the sheets together and force out the liquefied insulating material from between the sheets together with any contained air or moisture, forming a permanent filler of said insulating material around the stack in said casing without exposing the stack to atmosphere after the bath therein.

4. The method of making an insulation-embedded mica and foil condenser held compressed permanently by a clamp in a permanent casing enclosing the embedment, which consists in building a stack of sheets of mica and metal foil; assembling a permanent clamp with such stack and with a permanent casing around the stack and clamp; thereafter, before compressing the stack by such clamp, filling the casing around the stack with a permanent insulation-embedment comprising hot fluid insulating material which is solid at ordinary temperatures; thereafter applying heat until insulating material in fluid condition lies between the surfaces of the sheets of the stack; thereafter, while the insulating material between the sheets is fluid, subjecting the stack to high mechanical compression to bring the sheets closer together and squeeze out from between them the fluid insulating material and any air or moisture between the sheets; maintaining such close association of the sheets by maintaining such high compression by means of said permanent clamp; and thereafter solidifying the insulating material surrounding the stack as an embed-

ment while the stack is held under said compression by said clamp.

5. The method of making an insulation-embedded mica and foil condenser held compressed permanently by a clamp in a casing enclosing the embedment, which consists, first, in coating the sheets with an insulating liquid solid at ordinary temperatures but liquefiable by a degree of heat not injurious to the foils; building a stack of sheets so coated; assembling such stack with a permanent clamp in a permanent casing; then, before compressing the stack, filling the casing around the stack with a permanent insulation-embedment comprising hot fluid insulating material of the kind between the sheets of the stack; thereafter, while the insulating material between the sheets is in fluid condition, subjecting the stack to high mechanical compression to bring the sheets closer together and squeeze out from between them the fluid insulating material and air and moisture between the sheets; maintaining such close association of the sheets and the exclusion of air or moisture from between them by maintaining such high compression by said permanent clamp; and thereafter solidifying the insulating embedment while said compression yet is maintained by said clamp.

6. The method of making mica and foil condensers, which consists in building a stack of mica and foil sheets with insulation between them which is liquefiable at temperatures not injurious to the foils; thereafter placing such stack in its permanent casing; submerging the stack therein in a permanent embedment of insulating material like that between the sheets and solid at ordinary temperatures but now a hot fluid; applying heat to liquefy the insulating material between the sheets and drive out air from the fluid embedment; and applying and maintaining high pressure to the stack while the insulating material between the sheets is fluid and while the stack is submerged in the fluid insulating material to bring the sheets into closer relation and squeeze out the fluid insulating material from between them; and solidifying the insulating embedment; all whereby the stack is permanently embedded without exposing it to the atmosphere after its said submergence in the fluid embedment, and while maintained under the high pressure.

7. The method of making mica and foil condensers, which consists in building a stack of mica and foil sheets with insulating material between them which is liquefiable by a degree of heat which is not injurious to the foils and is solid at ordinary temperatures; thereafter placing the stack in its permanent casing while the same has a temporary extension applied thereto; filling the casing and extension with molten in-

- insulating material like that between the sheets, that is, which is solid at ordinary temperatures; applying heat to liquefy the insulating material between the sheets and 5 drive out air and moisture from the insulating material in the stack around the casing; and applying and maintaining pressure to the stack while hot and submerged in said insulating material, to bring 10 the sheets closer together and force out the fluid insulating material from between them; solidifying the insulating material surrounding the stack while maintaining said pressure; and then removing the 15 temporary extension from the permanent casing.
8. The method of making mica and foil condensers, which consists in building a stack of sheets with insulating material between them which is liquefiable by a degree 20 of heat which is not injurious to the foils and is solid at ordinary temperatures; thereafter placing such stack in a permanent casing; filling the casing with insulating 25 material like that between the sheets, that is, which is solid at ordinary temperatures and liquefiable by a degree of heat not injurious to the foils; applying heat to liquefy the insulating material between the 30 sheets while the stack is arranged to allow the escape of air during said heating from the insulating material surrounding the stack; and applying pressure to the stack while submerged in the fluid insulating
- material in the permanent casing, to bring 35 the sheets closer together and squeeze out the liquefied insulating material from between them; and solidifying the insulating material surrounding the stack from the bottom upward while maintaining the 40 pressure on the stack to prevent entrance of air or moisture between the sheets while the insulating material surrounding the stack is in fluid condition.
9. The method of making mica and foil 45 condensers, which consists in immersing a stack of foil and mica sheets, while substantially loosely assembled together, in a hot fluid insulating material which is solid at ordinary temperatures; supplying additional heat to the embedding material surrounding the stack to thoroughly heat the latter and establish a fluid condition of 50 insulating material between the sheets which is solid at ordinary temperatures; subjecting the stack while submerged in said fluid insulating embedment and while hot due to such additional heating, to high compression to squeeze out from between the sheets the 55 fluid insulating material and any air or moisture present between the sheets; and, while maintaining such compression, cooling and solidifying the insulating material around the compressed stack to constitute a permanent embedment preventing re- 60 entrance of air or moisture between the sheets of the stack.

GREENLEAF WHITTIER PICKARD.
